GARMENT CLAMP

Charles Leroy Allen, deceased, late of Drumheller, Alberta, Canada, by Donna Maude Allen, executrix, Drumheller, Alberta, Canada

Application January 3, 1956, Serial No. 557,124

4 Claims. (Cl. 223—91)

This device relates generally to hangars and particularly to improvements to garment clamps of the type attachable to a conventional wire coat hanger.

The principal object of this device is to provide a garment hanger attachable to the bottom bar of a coat hanger that will not move along the bar of the coat hanger unless adjusted manually.

A second object is to provide a garment hanger of this type that will not shake loose from the bar of the coat hanger.

An additional object is to provide a garment hanger that is attached firmly to the bottom bar of a coat hanger and is maintained thereon independently of the weight of garments suspended from the hanger.

Prior garment hangars of the type attachable to the bottom bar of a conventional coat hanger include the skirt hanger described and illustrated in Patent No. 2,129,455 issued September 6, 1938 to H. D. Wisehart et al. and the garment hanger described herein relates specifically to improvements to this hanger. As set out in this prior patent this skirt hanger comprises angularly disposed arms one of which terminates in a helical coil that is attachable to the bottom bar of a coat hanger while the other arm terminates in a garment clamp and the weight of a garment suspended in the garment clamp serves to cant the helical coil and maintain the coil in frictional engagement with the bottom bar of the coat hanger. The obvious disadvantage in a hanger of this type lies in the fact that once the garment weight is removed the helical coil is no longer canted into frictional engagement with the bottom bar of the hanger and the clamps may move freely on the bottom bar. In some instances the clamps have been found to move along the bottom bar of the hanger while a garment is suspended therefrom if the garment is for some reason moved upwardly momentarily to release the coil from engagement with the bar. In other instances it has been found that the ordinary movement of the hanger during transportation has been sufficient to release the helical coil from engagement with the bar and the hangars have become lost or mislaid.

An additional object of the present device therefore is to provide a garment hanger wherein the above recited disadvantages have been overcome. The improved construction leading to the elimination of these disadvantages will be seen clearly in reference to the attached drawings which form a part of the specification which should be read in the light thereof. It must be understood that the information disclosed in the specification and drawings is by way of example and illustration only and is not to be construed as a limitation.

In the drawings:

Figure 1 is a perspective view illustrating my improved garment hanger attached to the bottom bar of a conventional coat hanger and illustrating a garment in phantom lines suspended therefrom.

Figure 2 is a broken away perspective view showing my hanger attached to the bottom bar of a coat hanger

2

with a garment suspended therefrom in an alternate manner.

Figure 3 is a fragmentary front elevational view of the device.

Figure 4 is a fragmentary perspective view showing a coat hanger and with an alternative embodiment of my device attached thereto.

With reference now to the drawings it will be seen that my device comprises the arms 1 and 2 which are disposed angularly and are connected together by the helical coil 3. The arm 2 is terminated in a garment clamp which may be of the type designated generally by the numerals 4, 5 or 6. The arm 1 terminates in a hooked portion 7 whose function will be described later in the specification.

In operation my device is attached to a conventional coat hanger which is illustrated in Figure 1 in the drawings and comprises the hook 8, sides 9—9 and bottom bar 10. The device is attached to the bottom bar 10 of the coat hanger by hooking the coil 3 over the bar and then moving the arm 2 into a substantially vertical position to force the arm 1 upwardly and allow the engagement of the hook 7 with the bar 10. The bar 1 is of spring construction and when forced upwardly to engage the hook 7 with the bar 10 the coil 3 is canted sufficiently to maintain the coil in tight frictional engagement with the bar 1 and thereby prevent unwanted movement of the device along the bar 10. With the hook 7 engaged on the bar 10 it is necessary to apply upward pressure on the arm 2 to release the coil 3 and allow manual adjustment of the device along the bar 10.

As will be seen in Figure 1 in the drawing a garment 11 is suspended at one side in the garment clamp 4 which comprises the members 12 and 13 formed into a double inverted U to provide the grip 14 for the reception of the garment. Suspension at the opposite side is in the clamp 5 which comprises the fixed jaw 15 and movable jaws 16—16 held tensionably against the fixed jaw 15 by the coil springs 17—17. The springs 17—17 are attached at 18 to the fixed jaw 15. It will be seen also that the jaws 16—16 are provided at their outer ends with hooks 19—19.

Reference now to Figure 2 in the drawings will illustrate a garment 20 suspended at one side by the grip 14 as was described for the garment 11 and suspended at the opposite side on the hooks 19—19 which are extended through the loops 21—21 which could be the common belt loops on a pair of trousers, skirt or the like.

In the embodiment illustrated in Figure 4 in the drawings the arm 2 is formed into a single hooked portion 22 at the lower end thereof and it is intended that a garment be suspended on this hook 22 which would be inserted through belt loops 21—21 in a manner similar to that seen in Figure 2 in the drawings.

What I claim as my invention is:

1. In a garment hanger having a helical coil engageable loosely with the bottom bar of a coat hanger; a first arm fixed rigidly to the coil to extend downwardly with respect to the bottom bar of the coat hanger and terminating in a garment engaging clamp; a second arm fixed rigidly to the coil to extend therefrom at an angle with respect to the first arm, such second arm being movable to cant the coil into frictional engagement with the bar; a hook on the second arm engageable with the bar to maintain the coil in the canted position.

2. In combination with a coat hanger having a bottom bar, a garment hanger having angularly disposed arms, a helical coil interconnecting the arms and being engageable loosely with the bottom bar of the coat hanger, a garment clamp on one of the arms, the other arm being movable to cant the coil into frictional engagement with

the bar, a hook on the said other arm engageable with the bar to maintain the coil in the canted position.

3. A garment hangar as claimed in claim 1 wherein the garment clamp comprises a plurality of downwardly extending jaws, one of which is fixed, the remainder being movable tensionably with respect to the fixed jaw and having hooks thereon for engagement with a garment.

4. The garment hangar as claimed in claim 3 wherein

the movable jaws include coil springs fastened to the fixed jaw to maintain the movable jaws under tension with respect to the fixed jaw.
